UNITED STATES PATENT OFFICE.

ANTHONY T. SMITH, OF KANSAS CITY, MISSOURI.

STEAM ENGINE.

Application filed April 18, 1922. Serial No. 554,816.

To all whom it may concern:

Be it known that I, ANTHONY T. SMITH, a citizen of the United States, residing at Kansas City, in the county of Jackson and 5 State of Missouri, have invented certain new and useful Improvements in a Steam Engine, of which the following is a specification.

This invention has for its object to provide an improved valve structure especially designed for utilization in connection with steam engines of the type wherein two spaced and connected separate pistons are mounted for reciprocation in the cylinder, 15 the construction and arrangement of the valve being such as to alternately admit live steam to the opposite extremities of the cylinder to effect simultaneous reciprocation of the pistons, said valve also coacting with 20 exhaust ports communicating with the opposite extremities of the cylinder for alternately exhausting the steam therefrom.

A further object is the provision of a valve for engines of this type which shall 25 be of extremely simple and compact construction and wherein the movement of the valve is extremely limited and consequently its durability enhanced.

With these and other objects in view, the 30 invention consists in certain novel features of construction as hereinafter shown and described and then specifically pointed out in the claims and in the drawings illustrative of the preferred embodiment of the 35 invention.

In the accompanying drawing:

Figure 1 represents a side elevation of the improved engine, the crank shaft being broken away to illustrate the operating 40 mechanism for the valve.

Fig. 2 represents an enlarged fragmentary sectional view through the valve casing, and,

Fig. 3 represents a transverse sectional view on the line 3-3 of Fig. 2.

Figure 4 is a section on line 4-4, Figure 2.

Referring to the drawing in detail wherein similar reference numerals designate corresponding parts throughout the several views, the numeral 5 indicates a suitable supporting base having uprights 6 mounted centrally thereon supporting the steam engine cylinder 7. Cross head guides 8 are attached to one end of the cylinder 7 and are supported at their opposite extremities upon

a part of the engine frame. The crank shaft bearings are indicated at 9 and in which the crank shaft 10 is journaled. Spaced pistons 11 are mounted for reciprocatory movement 60 in the cylinder 7 and are connected by a piston rod 12 carrying a cross head 13 which latter is mounted to travel in the guides 8 and is connected by pitman 14 with the crank pin of the shaft 10. 65

The opposite extremities of the cylinder 7 are provided with lateral ports 15 designed to conduct steam to and from the extremities of the cylinder during reciprocation of the pistons 11. The central portion of the 70 cylinder 7 intermediate the pistons 11 is provided with a relief port 16 having communication with the atmosphere whereby any pressure between the inner opposed ends of the pistons is reduced to a minimum. 75

A substantially rectangular valve casing 17 is bolted or otherwise rigidly secured to the cylinder 7 and the opposite open extremities thereof communicate with the ports 15 formed in the opposite extremities of the 80 cylinder. Arranged within the casing 17 is a pair of vertical partitions 18' having the intermediate portions thereof curved, as at 19, and with the curved portions 19 oppositely disposed with respect to each other. 85 Projecting from the upper end of each of said partitions is a longitudinally disposed extension 25' of substantial length and from the lower end a longitudinally extending partition 27' of substantial length. The extensions 25', 27' of one partition 18' are oppositely disposed with respect to the extensions 25', 27' of the other partition 18'. 90

The casing 17, centrally of its top and bottom, is formed with an inwardly extending 95 nipple of substantial length and which is interiorly threaded. The inner edge of each of the nipples is of curved contour so as to form a continuation of the arc upon which the inner faces of the curved portions 100 19 of the partitions 18' extend.

The nipple carried by the top wall of the casing 17 is indicated at 20 and which depends into the casing 17 and has the curved inner end thereof indicated at 21'. The nipple 20 opposes for a portion of its length, as well as being spaced from both of the partitions 18'. Extending into the nipple 20 and threadably engaging therewith is a 105 steam supply pipe 21. 110

The nipple carried by the bottom wall of the casing 17 is indicated at 22 and which

projects upwardly into the casing 17 and has the curved inner end thereof indicated at 22'. The nipple 22 opposes for a portion of its length, as well as being spaced from, both of the partitions 18'. Extending into the nipple 20 and threadably engaging therewith is an exhaust pipe 23. The nipple 20 is arranged in vertical alignment with respect to the nipple 22.

10 The inner ends of the nipples 20 and 22, in connection with the inner faces of the curved portions 19 of the partitions 18' provide centrally of the casing 17, a valve chamber 18.

15 The nipple 20, in connection with the upper ends of the partitions 18' provides a pair of supply ports 24, adapted to communicate with a pair of oppositely extending supply passages 25, formed by the top wall 20 of the casing 17 in connection with the longitudinally disposed extensions 25', which are formed integral with and project from the upper ends of the partitions 18'. The supply passages 25 open into the casing 17, at

25 a point slightly removed from the ports 15.

The nipple 22, in connection with the lower ends of the partitions 18' provide a pair of exhaust ports 26, adapted to communicate with a pair of oppositely extending exhaust passages 27, formed by the bottom wall of the casing 17 in connection with the longitudinally disposed extensions 27', which are formed integral with and project from the lower ends of the partitions 18'. The exhaust passages 27 open into the casing 17, at a point slightly removed from the ports 15.

30 The passages 25 are arranged parallel with respect to the passages 27. The ports 24 are disposed at right angles to the passages 25, and the ports 26 are arranged at right angles with respect to the passages 27.

35 The ports 24, as well as the ports 26, are controlled by a valvular element 28, which is circular in contour and rides against the opposed inner faces of the curved portions of the partitions 18' and also against the inner ends of the nipples.

40 The valvular element 28 is an oscillatory one and is provided with diametrically opposed pockets 29 for alternately controlling the supply through the ports 24 and the exhaust through the ports 26.

The valvular element 28 is secured to an axial stem 30, which projects through an 55 aperture in the outer side wall of the casing 17, and connected to the stem 30 is a driving disk 31. In the alternate positions of the valve 18 the pocket 29 in the upper part thereof alternately connects the steam supply port 20 with the two inlet ports 24 whereas the lower pocket 29 alternately connects the exhaust pipe 23 with the two adjacent ports 26 and the arrangement of the pockets is such that as steam is being admitted to one terminal of the cylinder 7 through the ports 24 and 15, the steam in the opposite extremity of the cylinder 7 operating against the other piston 11 is being exhausted through the ports 15 and 26. 70

The disk 31 is provided with an eccentric pin 32 connected with a rod 33 having a strap 34 attached to the opposite extremity which embraces an eccentric 35 on the crank shaft 10 whereby longitudinal movement of 75 the rod 33 is effected during operation of the engine to produce an oscillatory movement of the disk 31 and also the valve 28.

What I claim is:

A steam engine comprising a cylinder having on one side at opposite ends a port, a casing opening into said ports and having aligning inwardly extending supply and exhaust nipples respectively at the top and bottom thereof, spaced vertical partitions 85 within said casing and having curved portions coacting with the inner ends of the nipples to form a circular valve chamber, said nipples in connection with said partitions providing a pair of inlet and a pair of outlet 90 ports, means extended from the upper and lower ends of said partitions and forming in connection with the top and bottom of the casing respectively a pair of oppositely disposed supply passages leading from said inlet ports and a pair of oppositely disposed exhaust passages leading to said exhaust ports, and a shiftable valve bearing against the wall of said chamber and having diametrically disposed pockets for alternately 95 opening said inlet ports and said exhaust ports. 100

In testimony whereof, I affix my signature hereto.

ANTHONY T. SMITH.
